HEMOGLOBINOMETER

Noah Holt, Pueblo, Colo.

Application May 28, 1932, Serial No. 614,226

11 Claims. (Cl. 88—14)

This invention relates to the class of measuring instruments and pertains particularly to a hemoglobinometer.

The primary object of the present invention is to provide an instrument by means of which the percentage content of hemoglobin in the human blood may be quickly and accurately determined.

Another object of the invention is to provide a hemoglobinometer which is relatively simple in construction and which does not require any particular scientific knowledge to use, thus making it possible for a physician to leave the determination of the hemoglobin content of blood specimens to an assistant with the assurance that an accurate report will be obtained.

A still further object of the invention is to provide a hemoglobinometer employing an electric illuminating element, in which the element is energized upon the application of the instrument to a supporting surface so that the specimen and a comparator may be illuminated to be viewed by the user to determine the quality of the specimen, the said specimen being divided in a series of receptacles of varying depth and the receptacles being adjustable relative to the comparator so that one thereof may be matched for color with the comparator or body which is of the color of normal blood.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

40. In the drawings:—

Figure 1 is a view partly in longitudinal section and partly in elevation of the preferred form of the instrument embodying the present invention;

Figure 2 is a sectional view taken substantially upon the line 2—2 of Figure 1;

Figure 3 is a sectional view taken substantially upon the line 3—3 of Figure 1;

Figure 4 is a perspective view of a detail of the instrument;

Figure 5 is a sectional view taken substantially upon the line 5—5 of Figure 2;

Figure 6 is a view partly in elevation and partly in section of a modified form of the invention;

Figure 7 is a transverse sectional view taken on the line 7—7 of Figure 6;

Figure 8 is a plan view of the runner used upon the modified form of the instrument;

Figure 9 is a sectional view taken on the line 9—9 of Figure 6.

Referring now more particularly to the drawings wherein like numerals of reference indicate corresponding parts throughout the several views, Figure 1 illustrates in section the preferred form of the present invention, as previously stated, wherein there is provided a casing 1 of 10 the character commonly employed in a hand flash-light, in which is mounted a battery cell 2, the upper end of which contacts with the base of an incandescent bulb 3 which is mounted in a reflector 4 in the usual manner.

One end of the cell casing 1 is closed by a cover 5 in which is a spring contact 6 and a reciprocable pin 7 attached thereto and extended through to the outside as shown, the battery cell 2 being maintained with its bottom in spaced relation to the cap 5 by any suitable means such as the ring of insulation material 8, so that the spring contact 6 is normally free from engagement with the bottom of the battery cell.

Upon the upper end of the casing 1 is mounted 25 a circular housing 9 having the top and bottom walls 10 and 11 respectively. Integral with the bottom wall is a threaded collar 12 which engages about the reflector end of the casing 1 in the manner illustrated so as to secure the housing 30 firmly on the casing.

The top wall 10 of the housing 9 has formed therethrough the three window openings 13, 14 and 15, the windows 13 and 14 being at opposite sides of the longitudinal center of the instrument so that the maximum amount of light from the incandescent bulb 3 will pass therethrough.

Secured over the window opening 13 is a ruby glass 16 which is of a shade of red corresponding with normal blood or blood having the proper percentage of hemoglobin therein.

The housing 9 includes an off-set portion providing a chamber 17, one side of which chamber is open as at 18. This chamber is preferably of rectangular design and the edge of the open side 45 18 is tangential with the circular side wall of the housing as illustrated in Figure 2.

Removably positioned in the chamber 17 is a relatively flat and broad rectangular frame which is shown in detail in Figure 4 and indicated generally by the numeral 19. This frame has the top and bottom walls 20 and 21 which are connected by the front and rear walls 22 and 23. The front wall 22 of the frame 19 is of a size to 50 tightly close the opening 18 when the frame is ex- 55

tended into the chamber 17 in the manner illustrated in Figure 2.

The top wall of the chamber 17 which is a continuation of the wall 10, has a slot 23' formed 5 therein from the edge of the opening 18 and the bottom wall of this chamber which is indicated by the numeral 24 and which is in a plane above the wall 11 of the housing, has a downwardly pressed off-set forming a groove 25 which 10 extends inwardly from the free edge of the opening 18 beneath and parallel with the slot 23'. The top and bottom walls 20 and 21 of the frame 19 are provided at adjacent edges with inwardly extending notches 26 as shown in Figure 4.

15 Removably positioned within the frame 19 is a disk 27, in one face of which is an annular channel 28 which is adjacent and opens through the peripheral wall of the disk. This channel is 20 transversely divided into areas 28' which are of gradually and progressively varying depth as 25 shown in Figure 5, starting at one point with an area of very shallow dimensions and continuing around the series, gradually increasing in depth, until the last area is relatively deep.

25 This disk 27 is made of a suitable translucent material such as white glass or porcelain, so that light from the bulb 3 will be diffused there-through and thus permit of an accurate matching of the color of the blood contents of these wells 30 with the comparator 16. The disk 27 has a central aperture 29 therethrough and designed to overlie this disk is a second disk 30 which is of 35 transparent glass and which also has a central aperture therethrough as indicated at 31, the disks 27 and 30 being of the same diameter.

40 These disks 27 and 30 are secured together with the disk 30 covering the specimen areas 28', by means of a screw 32 on which are the two nuts 33. The disks 27 and 30 are between the nuts 33 and 45 may thus be clamped tightly together thereby. When the disks are held in position on the screw 32 by the nuts 33 the unit made up of these disks, nuts and screw may be positioned in the frame 19 between the walls 20 and 21 thereof with the screw lying in the notches 26. The upper end of 50 the screw is provided with a knurled head 34 as illustrated to facilitate grasping and turning of the screw and the disks carried thereby. After the disks have been mounted in the frame 19 in the manner described, the frame is inserted into the chamber 17, the lower end of the screw 32 sliding in the groove 25 and the upper end positioning in the slot 23'. As a result of the right angular 55 relation between the notches 26 and the slot and groove 23' and 25, after the frame has been placed in the chamber, the screw 32 will be firmly held in position but will be permitted rotary movement.

60 The diameters of the disks 27 and 30 is such that any one of the areas 28' may be located directly under the window opening 14, the dimensions of the areas and of this window opening being the same and the peripheries of the disks do not extend beyond the portion of the top wall 10 of the housing which separates the window 65 openings 13 and 14 so that the ruby glass 16 will not be covered thereby.

70 The top surface of the disk 27 has thereon a number adjacent each area 28' which indicates the percentage amount of hemoglobin in the blood which when placed in the area corresponds in depth of color with the ruby glass 16. The deepest of the areas, of course, will be numbered to 75 indicate blood having a very low hemoglobin content, while the shallowest will be numbered to indicate blood having a higher hemoglobin con-

tent, the areas between being correspondingly graduated.

Slidable over the inner surface of the top wall 10 of the housing is a shutter element 35 which 5 may be shifted to cover the window opening 15. This window opening is in alignment longitudinally of the instrument with the area of the over-lying disk in which the hemoglobin percentage indicating figures lie. Any suitable means is provided for the operation of this shutter, as for 10 example, there may be employed a stem 36 attached to the shutter and extending outwardly over the top wall of the housing 9 as illustrated in Figures 2 and 3.

15 The top wall 10 of the housing 9 carries a sight tube 37 which is of sufficient diameter to enable a user of the instrument looking through the aperture 38 at the outer end thereof to clearly see the light from the lamp 3 passing through the window openings and consequently to see the ruby 20 glass 16, the areas 28' overlying the window opening 14 and the number adjacent such area when the shutter 35 is retracted.

25 In Figures 6 to 9 inclusive there is illustrated a slightly modified form of the instrument above described, the principle of this form being, however, the same. In this form of the instrument there is provided an elongated flat body 39 of porcelain or white glass in the top surface of 30 which is a longitudinally extending channel 40 divided into areas 40' and besides these areas and extending longitudinally of the series is a body 41 of ruby glass, the color of which is like 35 the ruby glass 16, the same as normal or healthy blood. The top surface of the body 39 is provided with a series of numerals each being transversely aligned with an area 40' and representing the percentage content of hemoglobin 40 in the blood specimen which when placed in the adjacent area compares in color with the ruby glass standard. This base body 39 is covered by a similarly shaped clear cover glass 42 and suitable means is employed for securing the glass and base together such, for example, as the thumb screws 43 which are illustrated. De- 45 signed to be mounted upon the bodies 39 and 42 after the same have been secured together by the thumb screws 43, is a slide 44 which has a sight opening 45 therein, which when the slide is in position extends across the two bodies so 50 that one of the areas 40' will be uncovered or in view and also a portion of the adjacent ruby glass and the number aligned transversely of the body with the pocket.

55 As the material of the slide 44 is of non-transparent character the adjacent areas will be covered so that an accurate comparison of the contents of one area with the ruby glass may readily be made. As in the preferred form of the instrument the shallowest of the areas 40' will have a number adjacent thereto which indicates a high percentage of hemoglobin and the deepest of the areas will indicate a low percentage of hemoglobin as a larger quantity of blood of low hemoglobin percentage will be required to match the ruby glass than would be required in a shallow area. The areas between the shallowest and deepest are of graduated depths as previously explained and the percentage indicating numbers are correspondingly graduated.

70 In the use of the present instrument, referring to the preferred form illustrated in Figure 1, the disks 27 and 30 are secured together and the annular recess 28 thereof is filled with blood by 75 touching the periphery of the disks at the re-

cess portion against a drop of blood which has been squeezed from the finger, ear lobe or any other suitable part of the body of the patient whose blood is being tested. Due to the shallowness of the annular channel, even at the deepest portion thereof, the blood will be drawn in by capillary attraction and distribute itself throughout the channel in the areas thereof completely filling the channel between the bottom and the under side of the cover glass. The disks are then placed in the frame 19 in the manner illustrated and the frame inserted into the chamber 17. By thus positioning the instrument uprightly upon a suitable supporting surface the contact 6 will be forced upwardly into engagement with the bottom contact with the cell 2 and the under side of that portion of the disk overlying the reflector 4 will be illuminated.

The operator then peers through the opening 38 and along the sight tube 37 toward the window openings 13, 14 and 15 and by grasping the knob 34 slowly rotates the disk until an area is found in which the color of the blood therein appears to correspond with the color of the ruby glass 16.

The window opening 15 will be kept covered by the shutter 35 while rotating the disks and comparing the contents of the pockets with the specimen glass so that no superfluous light will enter the sight tube and thus interfere with the matching of the colors. After the color of the contents of a pocket has been matched with the ruby glass then the window opening 15 may be uncovered so that light will be let through to illuminate the number adjacent the selected area of blood which indicates the percentage content of hemoglobin therein.

The formation of the areas 28' in the disk 27 may be regulated so that the one lying second from the shallowest thereof will contain the proper amount of normal blood or blood containing the normal amount of hemoglobin, to match the color of the ruby glass. By this arrangement the areas will gradually decrease in depth in one direction from this intermediate area and will, when filled with normal blood gradually shade off lighter and lighter to the shallowest of the pockets, while those pockets lying on the other side of the intermediate pocket will gradually show darker and darker shades until the deepest pocket is reached.

The operation of the modified form of the invention shown in Figures 6 to 9 inclusive will be readily understood from the foregoing description given in connection with the preferred form of the invention, the comparison here being made by moving the slide or runner 44 longitudinally of the bodies 39 and 42 after filling the areas 40' with the blood to be tested until the sight opening aligns an area of blood which corresponds in color with the ruby glass 41 lying adjacent thereto.

The numeral simultaneously uncovered or viewed through the sight opening 45 will indicate the percentage hemoglobin content of the blood specimen under examination.

Having thus described the invention, what is claimed is:—

1. A hemoglobinometer comprising a housing having top and bottom walls, a disk of translucent material rotatably mounted in the housing and having an annular series of blood areas in one face, the areas being of graduated depths, supporting means for said disk permitting the ro-

tation thereof in a plane parallel with the top wall of a housing, a pair of window openings in said top wall, one thereof being located above the disk in a position for the selective location of said areas therebeneath, a ruby glass covering the other window, means for projecting light through said disk toward the windows and ruby glass, and means for viewing the ruby glass and the blood area located under the window adjacent thereto.

2. A hemoglobinometer comprising a body forming a housing having top and bottom walls, an illuminating element, a casing for said illuminating element, means integral with the bottom wall of the housing for securing the latter over the illuminating element, said top wall having a pair of window openings therein overlying the said element, means for viewing said windows, a translucent body having an annular series of areas therein of graduated depths, means for mounting said translucent body for rotation in the housing in a position for the selective location of said areas under one of said windows, a ruby glass covering the other of said windows, a transparent covering means for the translucent body, means for rotating the cover means and the adjacent body, and data disposed adjacent the areas for indicating the percentage hemoglobin content of a blood specimen in any one of the areas which corresponds in color with the ruby glass.

3. A hemoglobinometer comprising a body forming a housing having top and bottom walls, an illuminating element, a casing for said illuminating element, means integral with the bottom wall of the housing for securing the latter over the illuminating element, said top wall having a pair of window openings therein overlying the said element, means for viewing said windows, a translucent body having an annular series of areas therein of graduated depths, means for mounting said translucent body for rotation in the housing in a position for the selective location of said areas under one of said windows, a ruby glass covering the other of said windows, a transparent covering means for the translucent body, means for rotating the cover means and the adjacent body, and data disposed adjacent the areas for indicating the percentage hemoglobin content of a blood specimen in any one of the areas which corresponds in color with the ruby glass, said top wall having a third window opening, and shiftable cover means for said third opening, said third opening when uncovered permitting the projection of light through the translucent body to illuminate the data adjacent the pocket being viewed.

4. A hemoglobinometer of the character described comprising a cylindrical casing containing a battery cell, reflector and incandescent element in the reflector, switch means for energizing said incandescent element, a housing having a substantially circular portion and an off-set rectangular portion, the said rectangular portion having one side wall open and further having top and bottom walls, said top wall having a pair of window openings therethrough, means for securing said housing to said casing with said window openings over the incandescent element and reflector, a body removably positioned in the rectangular portion of the housing and having a wall closing the open side thereof, a rotatable unit removably mounted in said body consisting of a disk of translucent material having an annular series of areas in one surface thereof of graduated depths, a transparent cover glass overlying the

areas, a screw extending through the translucent body and cover glass, means carried by the screw and at opposite sides of the translucent body and cover glass for securing the two together, one end of said screw being located exteriorly of the housing, means for supporting said screw vertically in the housing and first mentioned body to permit rotation thereof and the translucent body and cover glass, said translucent body being so positioned as to permit the selective location of any one of said areas under one of said windows, and a ruby glass covering the other of said windows.

5. A hemoglobinometer comprising a flat body 15 of translucent material, a longitudinally extending series of areas formed in one face of said body, said areas being of graduated depths and merging directly one into the other, a ruby glass mounted adjacent said areas, data disposed adjacent each area to indicate the percentage hemoglobin content of a blood specimen in an area which corresponds in color with the adjacent ruby glass, and means for focusing the sight upon a selected area and the adjacent ruby glass 25 and data consisting of a slide mounted upon the translucent body for movement longitudinally therealong and having a rectangular sight opening extending transversely thereof.

6. A hemoglobinometer comprising a flat body 30 of translucent material, a longitudinally extending series of areas formed in one face of said body, said areas being of graduated depths and merging directly one into the other, a ruby glass mounted adjacent said areas, data disposed adjacent each area to indicate the percentage hemoglobin content of a blood specimen in an area which corresponds in color with the adjacent ruby glass, means for focusing the sight upon a selected area and the adjacent ruby glass and 35 data consisting of a slide mounted upon the translucent body for movement longitudinally therealong and having a rectangular sight opening extending transversely thereof, and a transparent cover glass overlying and secured against the areaed face of the translucent body and disposed beneath the slide.

7. In a hemoglobinometer, a housing having a 40 wall opening and a pair of windows in a wall, a frame slidable into the housing through said opening, a pair of concentric disks carried by said frame, one thereof being translucent and having a channel in one face adjacent the edge and formed to provide areas of progressively changing depth, the other disk being transparent, said areas being viewable through a window, a ruby glass covering the other window, said windows being in relatively close proximity, illuminating means for the housing between which means and the windows a peripheral portion of the disks is located, and means carried by the frame for rotatably supporting the disks whereby any one of said areas may be brought to position beneath the window adjacent the ruby glass.

8. In a hemoglobinometer, a housing having a 45 wall opening and having a wall provided with a pair of relatively closely positioned windows, a frame slidable in said housing through said wall opening, a channel formed in a wall of the housing, a pair of concentric disks one of which is formed of translucent material and has a channel in one face adjacent the edge and formed to provide a series of areas of progressively changing depth, the other disk being transparent and overlying said channel, a stem extending concentrically through the disks, means carried on the stem

for securing the disks together, said disks and securing means being mounted in the frame, the disks having a portion of the periphery projecting from the frame and located beneath one of said windows when the frame is in the housing, said stem having its lower end slidably engaged in said channel and having its upper end projecting beyond the top of the housing, a ruby glass in the other of said windows, and means for illuminating the interior of the housing, between which means and said windows a portion of the periphery of the disks is located whereby one of said areas may be viewed through the window adjacent the ruby glass.

9. In a hemoglobinometer, a housing having a 15 wall opening and having a wall provided with a pair of relatively closely positioned windows, a frame slidable in said housing through said wall opening, a channel formed in a wall of the housing, a pair of concentric disks one of which is 20 formed of translucent material and has a channel in one face adjacent the edge and formed to provide a series of areas of progressively changing depth, the other disk being transparent and overlying said channel, a stem extending concentrically through the disks, means carried on the stem 25 for securing the disks together, said disks and securing means being mounted in the frame, the disks having a portion of the periphery projecting from the frame and located beneath one of said windows when the frame is in the housing, said stem having its lower end slidably engaged in said channel and having its upper end projecting beyond the top of the housing, a ruby glass in the other of said windows, and means for illuminating the 30 interior of the housing, between which means and said windows a portion of the periphery of the disks is located whereby one of said areas may be viewed through the window adjacent the ruby glass, one of said disks having indicia designed to 35 be viewed in relation with said areas, a third window adjacent said first windows, and means for covering said third window while viewing the ruby glass and the disks through the window adjacent the ruby glass.

10. In a hemoglobinometer, a body of translucent material having a channel formed therein adjacent to and opening through one edge and also open through the top of the body, said channel being relatively broad as compared to its depth 50 and having the bottom divided into a series of flat areas arranged in progressively changing planes from one end of the series to the other, a transparent cover for said channel, a comparator of the color of normal blood, and means for selectively directing the sight toward any one of said areas and the comparator.

11. In a hemoglobinometer, an elongated flat body of translucent material having a channel formed therein along one edge and opening 60 through the said edge and through the top surface of the body, said channel having the bottom divided into a series of flat areas arranged in progressively changing planes from one end of the channel to the other, an elongated comparator 65 of the color of normal blood disposed in a channel in the body at the inner side of said first channel, a transparent cover overlying the body, said comparator and the first channel, a slotted guide slidably mounted upon the body and having the slotted portion extending across the comparator and the first channel, and index means on the body 70 for determining the condition of a blood sample in the first channel relative to the comparator.
